(57) **CLAIM**

We claim the ornamental design for a dieter's computerized scale having barcode scanner and alphanumeric input for displaying contents of food intake such as calories, fat, and the like, as shown and described.

DESCRIPTION

FIG. 1 is a perspective view of a dieter's computerized scale having barcode scanner and alphanumeric input for displaying contents of food intake such as calories, fat, and the like showing our new design with a lid thereof in an opened condition;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
